UNITED STATES PATENT OFFICE.

HANS WILHELM CHRISTIAN SCHRÖDER, OF LUBECK, GERMANY, ASSIGNOR TO DR. ING. H. C. ALEXANDER BERNHARD DRÄGER, OF FINKENBERG, LUBECK, GERMANY.

APPARATUS FOR ADMINISTERING ANÆSTHETIC GASES.

Application filed August 14, 1925. Serial No. 50,311.

To all whom it may concern:

Be it known that I, HANS WILHELM CHRISTIAN SCHRÖDER, a German citizen, residing at Lubeck, Germany, have invented 5 certain new and useful Improvements in Apparatus for Administering Anæsthetic Gases, of which the following is a specification.

The invention relates to an improved 10 method of and apparatus for administering gases and the like, particularly in simultaneously administering two or more different gases and the like.

In the well known method of and apparatus for the inhalation of two different gases, vapor or the like, for the purposes of therapeutic or clinical treatment, for instance of a nutrient gas and of a gaseous anæsthetic, the quantity of gas required for 15 satisfying the requirement of breathing during the whole time of treatment, as well as the anæsthetic, were taken from storage containers and supplied to the patient in a continuous manner, whilst maintaining the 20 proportion of the gas mixture required to ensure anæsthesia, for instance of 50% nutrient gas and 50% gaseous anæsthetic. This means however a bad utilization of the 25 existing stock of gas, more particularly a waste of the expensive anæsthetic. Moreover other persons in the room are greatly inconvenienced by the gases which the body 30 of the patient fails to absorb.

The present invention aims at eliminating the drawbacks above referred to. This is done by providing from the first in the mixing chamber and in the tube, a stock 35 of gas sufficient for a deep respiration, which is alternately inhaled and exhaled out, 40 whilst the quantity of nutrient gas required for the life processes, is supplied in a continuous current. On the contrary, the supply of the therapeutically or clinically active gas is entirely or partly cut off after the 45 saturation of the blood has taken place. In order to overcome a difficulty which is more particularly felt by beginners, namely that of correctly measuring by the depth of respiration, the gas quantity required, it is 50 advisable at the beginning of the treatment to supply ample gas and to discharge the small excess outwards through a spring or throttle valve provided in the exhaling tube. This has the advantage that not only no de-

ficiency of gas occurs, but that a uniform 55 pressure is ensured in the gas circulation system, and that the proportion of mixture of gases can be maintained more accurately with a small excess of supply over the consumption. 60

A construction of the apparatus for carrying out the invention is shown by way of example in the accompanying drawing, partly in section and partly in elevation.

The steel cylinder *a* contains the nutrient gas (air or oxygen), the steel cylinder *b* a gaseous anæsthetic (laughing gas, carbonic acid, acetylene etc.). By means of the dosing pressure reducing valve *c*, a given oxygen current consumed by breathing (in the case of grown up persons about 1.5 liter per minute) is set, by adjusting in the usual manner the set screw *d* and reading on the pressure gauge *e*. The current of gaseous anæsthetic is first set at the dosing pressure 70 reducing valve *f* to the amount required to produce a given depth of anæsthesia, and later on throttler or shut off, also by operating a set screw *g* and observing the pressure gauge *h*. Instead of combining the 75 pressure reduction and gas dosing in one valve *e, f*, separate fittings could be provided for each operation.

The nutrient gas passes to the storage bag *m* through the tube or pipe *i*, and the gaseous anæsthetic through the pipe *k*. The storage bag in inflated state must be so large as to be able to supply a powerful lung with gas in the case of a deep inhalation, or receive all the gas exhaled in the case of a 90 deep exhalation (about 5 liters). The patient inhales the gas mixture from the bag *m* through the check valve *n*, tube *o* and the face mask *p*. The bag becomes then for the most part emptied as it receives from the pipes *i* and *k* only a slight additional supply of gas; at the end of the exhalation stage, it will be however completely filled again, as the exhaled air will be returned to the bag *m* through the tube *q*, check valve 95 *r*, three way cock *s*, pipe *u*, chemical container *t* and pipe *v*, or the three way cock *s*, pipe *u'* and pipe *v'*. The quantity of the gas exhaled is reduced only: firstly by the amount 100 of the nutrient gas consumed in the body of the patient, about 5% of the quantity inhaled, and secondly by the quantity of gaseous anæsthetic required for a given degree 105

of saturation, which again amounts only to a portion of the above 5%, and eventually can sink to 0.

In the chemical container *t*, the air exhaled is freed from carbonic acid. If however the carbonic acid is not to be removed, or to be only partly removed, in order to have a stimulant for the breathing centre in the case of an insufficiently strong respiration, the admission to the chemical container is partly or entirely closed by means of the three way cock *s*, and instead, the admission to the by-pass *u*' is opened. In order to attain a more accurate addition of carbonic acid, the carbonic acid exhaled must be completely absorbed, and fresh carbonic acid supplied to the storage bag in the same way as the other two gases by means of a dosing valve.

If owing to an excessive supply of gas, a certain excess of pressure is produced in the exhalation pipe, it is discharged, according to the invention, into the atmosphere through an excess relief valve. In the construction illustrated, such an adjustable and automatically acting relief valve *w* which could be made for instance in the form of a spring controlled or throttle valve, is provided in the return piping section *v*, preferably in a branch *w*' of the same, which could be further provided also with a cock *x*.

I claim:

1. In an apparatus for administering anaesthetic gases by inhalation, the combination of a mixing chamber for containing a mixture of said gases, an inhalation pipe, a bifurcated exhalation pipe having two branches leading to said mixing chamber, a carbonic acid absorption device in one of said branches, and a three-way cock in said exhalation pipe whereby exhaled air is conveyed back to the mixing chamber at will through one or the other of said branches or through both branches simultaneously.
2. In an apparatus for administering anaesthetic gases by inhalation, the combination of a mixing chamber for containing a

mixture of said gases, an inhalation pipe, a bifurcated exhalation pipe having two branches leading to said mixing chamber, a carbonic acid absorption device in one of said branches, and a three-way cock in said exhalation pipe whereby exhaled air is conveyed back to the mixing chamber at will through one or the other of said branches or through both branches simultaneously, and an automatically acting relief valve in said exhalation pipe in communication with both branches thereof whereby excess gaseous fluid is automatically discharged.

3. In an apparatus for administering anaesthetic gases by inhalation, the combination of a mixing chamber for containing a mixture of said gases, an inhalation pipe, a bifurcated exhalation pipe having two branches leading to said mixing chamber, a carbonic acid absorption device in one of said branches, a check valve in each of said inhalation and exhalation pipes, and a three-way cock in said exhalation pipes whereby exhaled air is conveyed back to the mixing chamber at will through one or the other of said branches or through both branches simultaneously.

4. In an apparatus for administering anaesthetic gases by inhalation, the combination of a mixing chamber for containing a mixture of said gases, an inhalation pipe, a bifurcated exhalation pipe having two branches leading to said mixing chamber, a carbonic acid absorption device in one of said branches, a check valve in each of said inhalation and exhalation pipes, and a three-way cock in said exhalation pipes whereby exhaled air is conveyed back to the mixing chamber at will through one or the other of said branches or through both branches simultaneously, and an automatically acting relief valve in said exhalation pipe in communication with both branches thereof, whereby excess gaseous fluid is automatically discharged.

HANS WILHELM CHRISTIAN SCHRÖDER.
